LIFTING JACK CONSTRUCTION

Louis Schweitzer, Royal Oak, Mich., assignor to
 Motor Products Corporation, Detroit, Mich., a
 corporation of New York

Application January 16, 1950, Serial No. 138,905

8 Claims. (Cl. 254—106)

This invention relates to lifting jacks and refers more particularly to improvements in jacks of the type used in connection with road vehicles for raising a selected ground engaging wheel.

It is an object of this invention to provide a light weight jack capable of lifting substantial loads with no danger to inexperienced users and composed of a relatively few simple parts capable of being inexpensively manufactured and assembled.

The simplicity, ease and safety of operation of the jack is due largely to the use of sliding wedge type locking devices in place of the usual ratchet or rack and gear types of lifting mechanisms. In accordance with this invention, at least two wedge type locking devices operate in conjunction with one another to elevate the lift and cooperate to securely hold the lift in any one of its raised positions.

It is a further object of this invention to provide a jack of the above type wherein the wedge devices are alternatively moved upwardly by an arm to raise the jack lift step by step and wherein provision is made for releasing the wedge devices to permit lowering of the lift without manipulating the arm. As a result, the jack may be lowered with ease and the danger of the arm striking the user is avoided.

The foregoing as well as other objects will be made more apparent as this description proceeds especially when considered in connection with the accompanying drawings wherein:

Figure 1 is a side elevational view of a weight lifting jack embodying the features of this invention;

Figure 2 is a longitudinal sectional view through the lower portion of the jack;

Figure 3 is an enlarged vertical sectional view through a part of the jack shown in Figure 1;

Figure 4 is a sectional view taken on the line 4—4 of Figure 2;

Figures 5 and 6 are sectional views taken respectively in the lines 5—5 and 6—6 of Figure 4;

Figure 7 is a sectional view taken on the line 7—7 of Figure 5.

The jack selected herein for the purpose of illustration is especially adapted for the purpose of raising one or more of the ground engaging wheels of a road vehicle and the nature of the operating mechanism renders the jack highly suitable for applications wherein a substantial stroke or movement of the elevating part is required such, for example, as is the case with so-called bumper jacks.

The lifting jack shown in Figures 1 and 2 of the drawings comprises a base 10, a column 11, an elevating part 12 and lifting mechanism 13. The base 10 is shown in the form of a sheet metal stamping having an elevated portion 14 centrally apertured to receive a socket 15. The socket 15

is open at the top and has a lateral flange 16 which overlaps the top surface of the elevated base portion 14. A slot 17 is formed in one side of the socket 15 and a resilient strip 18 extends across the slot at the outer side of the socket. The upper end of the strip is secured in place by the flange 16 and the lower end of the strip is crimped around the bottom edge of the socket. The resilient strip is bent intermediate the ends to provide a loop 19 which projects into the socket 15 through the slot 17.

The column 11 is also preferably formed of sheet metal and is shown in Figure 4 of the drawings as being channel-shaped in cross section. The opposite side walls 20 and 21 of the column are provided with laterally inwardly projecting flanges 22 which terminate short of one another to provide a longitudinally extending slot 23 therebetween. Also, the flanges 22 cooperate with the remaining portions of the column to form a vertically extending guideway 24.

As shown in Figures 2 and 6 of the drawings, the lower end of the column is adapted to fit within the socket 15 and the side wall 21 of the column is formed with opening 25 adjacent the bottom of the column. The opening 25 is positioned to register with the slot 17 and to receive the loop 19 of the resilient strip 18 in the assembled position of the column with respect to the socket. The loop 19 of the spring 18 provides a resilient detent for removably holding the column 11 in a vertical position on the base 10.

The elevating part 12 is shown in the several figures of the drawings as comprising a pair of elongated channel-shaped sections 26 positioned with the channels opening toward one another and of a size to receive the vertical column 20, as shown in Figure 4 of the drawings. The sections 26 are secured in assembled relationship by a pad or support 27 in the form of a sheet metal stamping. The pad 27 is shown in Figures 1 and 2 of the drawings as extending laterally with respect to the column and as having laterally spaced projections 28 at the inner end. The projections 28 are shown in Figure 4 of the drawings as respectively overlapping the outer sides of the sections 26 and are welded, brazed or otherwise permanently secured to the sections 26. Thus the pad or support 27 functions to permanently secure the two sections 26 of the elevating part 12 in assembled relationship. The pad or support 27 also serves as a rest for engaging a part of a vehicle to lift the same when required.

The lifting mechanism 13 comprises an operating member 29, a pair of locking devices 30 and 31 and a releasing member 32. The locking devices 30, 31 are slidably supported within the guideway 24 and it will be noted from Figures 2 and 5 of the drawings that the device 30 is sup-

ported in the guideway directly above the device 31.

The locking device 30 is provided with a pair of wedges 33 and 34 slidably supported one above the other within the guideway 24. The adjacent ends of the wedges are inclined in a direction extending transversely to the guideway 24 and provide overlapping surfaces 35 and 36 on the respective wedges.

The locking device 31 also comprises a pair of wedges 37 and 38 slidably supported within the guideway 24 with the wedge 37 positioned above the wedge 38 in vertical alignment with the latter. The adjacent end portions of the wedges 37 and 38 are inclined with respect to the guideway 24 to provide overlapping surfaces 39 and 40 on the respective wedges. As shown particularly in Figure 5 of the drawings, the two pairs of wedges are similar in construction but are relatively positioned so that the overlapping surfaces 39 and 40 on the respective wedges 37 and 38 are inclined in a direction opposite the direction of inclination of the corresponding surfaces on the wedges 33 and 34.

As shown in Figure 7 of the drawings the opposite ends of the springs 41 are turned laterally and respectively project into elongated slots formed in the wedges of each pair 30 and 31. The springs 41 merely serve as ties between the respective wedges in the pairs 30 and 31 in order to permit movement of the wedges in each pair as a unit in an upward direction. The strength of the springs 41 is not sufficient to cause jamming of the wedges against adjacent sides of the guideway 24.

A member 42 in the form of a thin flexible metal strip is shown in Figure 5 as located within the guideway 24 and as extending in the general direction of the length of the guideway. The flexible strip 42 extends downwardly along the inner surface of the side 20 of the channel-shaped column and is extended between the overlapping surfaces 35 and 36 of the wedges 33 and 34 to the opposite side wall 21 of the column. The intermediate portion 43 of the strip continues downwardly along the inner surface of the side 21 and is extended between the overlapping surfaces 39 and 40 of the wedges 37 and 38. The lower end 44 of the strip continues downwardly along the inner surface of the side 20 to a point adjacent the bottom of the column wherein it is secured to the column. The upper end of the flexible strip extends for a substantial distance above the locking device 30 and is also secured to the column.

Attention is called to the fact that the intermediate portion 43 of the flexible member or strip is not fastened to the adjacent side of the guideway 24 and as a consequence does not interfere with the required movement of the wedges. The purpose of the flexible member 42 is to hold the wedges in frictional contact with the sides of the guideway 24 so that only a slight relative movement of the wedges of either locking device toward one another is sufficient to cause jamming of the wedges against adjacent sides of the guideway 24.

The above arrangement is such that when the force is applied in an upward direction to the wedge 33, the overlapping or wedging surface 35 is moved away from the coacting surface 36 on the lowermost wedge 34 so that both wedges 33 and 34 may be readily moved in an upward direction within the guideway 24. This is also true of the second pair of wedges of the locking

device 31, although the two pairs of wedges are independently movable along the column.

A downward force applied to the uppermost wedge of each pair causes these wedges to move relative to the guideway 24 in a direction toward the adjacent bottom wedges. The slots into which the laterally turned ends of the springs 41 project are of sufficient size to permit the required movement of the top wedges 33, 37 toward the bottom wedges 34 and 38. As a result of downward movement of the top wedges in directions toward the bottom wedges, the oblique wedging faces 35, 39 on the respective top wedges 33, 37 press against the adjacent portion of the flexible strip 42 and apply a laterally outward force component against the oblique wedging surfaces 36, 40 of the bottom wedges 34 and 38 respectively. Thus the wedges of each pair are shifted laterally outwardly and are jammed against the adjacent sides of the guideway 24. In other words, the wedges of each pair become frictionally locked against further downward movement relative to the guideway 24.

Releasing of the wedges may be readily accomplished by merely applying a downward force on the lowermost wedges of each pair. This application of force moves the lowermost wedges downwardly slightly relative to the uppermost wedges and enables the locking devices to be freely moved downwardly in the guideway 24. This releasing action is accomplished in the present instance by manipulating the member 32 which will be presently described in detail.

As shown in Figures 1 to 3 inclusive, the wedge 33 is provided with a lateral outwardly extending projection 45 and the wedge 37 is provided with a similar projection 46. The projections 45 and 46 extend through the slot 23 in the column 11 and also respectively project through elongated slots 47 and 64 formed in the lifting device 12. The wedges 34 and 38 are respectively provided with lugs 49 and 50. These lugs also extend through the slot 23 in the column 11 and respectively project through slots 51 and 52 formed in the adjacent wall of the lifting part 12.

The operating member 29 has a socket part 53 shaped at one end to slidably receive a suitable tool 54 and having the other end connected to the projection 45 by pivot pin 46' in a manner to enable swinging movement of the part 53 in a vertical plane. The socket part 53 is also connected to the lug 46 by a lever 55. The upper end of the lever 55 is pivoted to the part 53 at a point spaced outwardly from the pivot 46 and the lower end of the lever is pivoted to the projection 46.

The releasing member 32 comprises a plate 56 extending in the direction of length of the column, and positioned at the outer side of the elevating part 12. As shown particularly in Figure 3 of the drawings, the plate 56 is provided with slots 57 and 58 for respectively receiving the projections 45 and 46. Also the releasing plate 56 is fashioned with slots 59 and 60 for respectively receiving the lugs 49 and 50. The upper end of the plate has a laterally inwardly extending lug 61 which projects over the adjacent end of the elevating part 12 so as to be moved as a unit with the latter. A suitable operating element 62 is secured to the releasing plate 56 adjacent the lower end in a position to be conveniently engaged by a foot of the user.

Operation

Assuming that the wedge parts of the jack previously described are in the relative positions

5

shown in Figure 2 of the drawings, and that it is desired to raise the lifting part 12 relative to the column 11, the operator causes the member 29 to be swung downwardly. The resulting force is transferred to the wedge 37 through the lever 55, and since the wedge 37 is locked against downward sliding movement in the guideway 24, the wedge 33 together with the wedge 34 is moved upwardly in the guideway 24. Upward movement of the wedge 33 causes the projection 45 to engage the shoulder 63 on the elevating part 12 and moves the latter upwardly along the column 11.

Upon completion of the above, the operator raises the member 29 and as a result applies a downward force on the wedge 33 and a lifting force on the wedge 37 through the lever 55. Since the wedge 33 is locked against downward movement in the guideway 24, the wedge 37 together with the wedge 38 is moved upwardly along the guideway 24. As shown particularly in Figure 3, upward movement of the wedges 37, 38 causes the projection 46 on the wedge 37 to engage the top wall 64 of the slot 48 in the part 12 and moves the latter upwardly.

It follows from the above that successive movement of the operating member 29 in opposite directions causes the locking devices 30 and 31 to alternately move upwardly with a step by step movement. Inasmuch as the elevating device 12 is moved as a unit with the locking devices, it follows that the pad 27 supporting the part to be raised is also elevated.

When it is desired to release the jack, or in other words, lower the elevating device 12, the operator merely applies a downward thrust on the part 62 connected to the plate 56. Slight downward movement of the plate 56 causes the upper walls of the slots 59 and 60 to respectively engage the projections 49 and 50 on the respective wedges 34 and 38. As a result these wedges are moved downwardly relative to their companion wedges and both locking devices are released permitting the elevating device 12 to slide downwardly along the pedestal 11. It is possible with the above construction to effect periodical downward movement of the elevating device by merely successively applying a releasing pressure on the part 62. In any case the releasing action does not cause the operating member 29 to "kick" in either direction and endanger the operator. In fact the operator may release the jack from a safe position with respect to either the jack or the vehicle.

What I claim as my invention is:

1. A lifting jack comprising a base, a column supported at its lower end on the base, an elevating part supported by the column for sliding movement lengthwise of the column, a pair of locking devices supported by the column for vertical sliding movement relative to the column, each locking device comprising a pair of vertically aligned wedges having adjacent overlapping surfaces at the inner sides inclined with respect to the path of sliding movement of the devices, abutment surfaces on the column extending vertically in the direction of sliding movement of the locking devices and respectively engageable with the outer sides of the wedges, means connecting the wedges of each pair permitting limited relative sliding movement of the wedges, an

6

operating member respectively connected to the uppermost wedge of each pair for alternatively moving the locking devices upwardly relative to the column, and means on the elevating part respectively engageable by the uppermost wedges of each pair to impart a lifting movement to said part.

2. The lifting jack set forth in claim 1 in which a releasing member is respectively connected to the lowermost wedge of each pair for releasing the wedges and permit lowering of the elevating part.

3. The lifting jack set forth in claim 1 in which the wedges of each pair are connected by a spring element, and in which a flexible strip extends between the overlapping wedge surfaces of each pair of wedges and has end portions which project beyond the locking devices between the abutment surfaces and the adjacent outer sides of the wedges.

4. The lifting jack set forth in claim 1 in which the column has a vertically extending channel-shaped guide, and in which the locking devices are slidably supported in the guide one above the other.

5. The lifting jack set forth in claim 4 in which a thin flexible strip has the opposite end portions respectively secured to one side of the channel beyond the locking devices and has an intermediate portion respectively extending between the overlapping wedge surfaces of each pair of wedges to the opposite side of the channel guide.

6. A lifting jack comprising a base, a column supported at its lower end on the base and having a vertically extending channel-shaped guide, a pair of locking devices supported in the guide one above the other and slidable along the guide relative to the column, each locking device comprising a pair of vertically aligned wedges having adjacent overlapping surfaces at the inner sides inclined in a direction extending transversely of the guide, spring means respectively connecting the wedges of each pair, an operating member having one end portion pivoted to

40 the uppermost wedge of the top locking device for swinging movement in a vertical plane, a lever having one end pivotally connected to the uppermost wedge of the bottom locking device and having the other end portion pivoted to the operating member at a point spaced from the pivoted end of said member whereby swinging movement of the member in opposite directions alternatively moves the locking devices upwardly along the guide, and an elevating part supported 45 by the column and connected to the locking devices for operation by the latter.

7. The lifting jack set forth in claim 6 having a member supported by the column for sliding movement relative thereto and having portions 50 respectively engageable with the lowermost wedges of each pair for releasing said wedges.

8. The lifting jack set forth in claim 7 having a thin flexible strip extending between the overlapping surfaces of the wedges of each pair and having end portions secured to the column beyond the locking devices to permit movement of the devices along the guide.

LOUIS SCHWEITZER.
